UNITED STATES PATENT OFFICE.

ERNEST UNGER, OF NEW YORK, N. Y.

CHANDELIER.

1,406,508.

Specification of Letters Patent. Patented Feb. 14, 1922.

Application filed July 28, 1921. Serial No. 488,068.

To all whom it may concern:

Be it known that I, ERNEST UNGER, a citizen of the United States, and resident of New York city, in the county of New York and State of New York, have invented certain new and useful Improvements in Chandeliers, of which the following is a specification.

The invention relates in general to an overhead bracket or chandelier for supplying electric current to a plurality of outlets and specially relates to such a chandelier for supplying current to a plurality of hair waving heating units for use in waving or otherwise treating the hair on a person's head and for supporting the supplied heaters in adjustable operative relation to the person's head.

It will be understood that in the art of hair waving of the type generally known as permanent hair waving, strands of hair properly wound on curling sticks are inserted in the bores of small tubular electric heaters which are assembled as closely together as is physically possible and positioned close to the person's head. It is usual in such devices to counterbalance the weight of the heaters so as to remove, in so far as is possible, all strains or pulls on the person's head and for this purpose numerous counterbalancing constructions have been used heretofore with chandeliers of the general type under discussion. With the development of the art of hair waving and with the reduction in size of the individual heaters, more and more heaters are used, so that at present it is not unusual to have as many as 48 heaters in use on a person's head at one time. As it is necessary to adjust the position of each heater there results an equal number of counterbalancing constructions, one for each heater, and, as the overall dimensions of such devices must be confined within relatively narrow spaces, the problem of providing an arrangement of such a large number of counterbalancing devices within narrow available space limitations has become difficult and this problem was further complicated by the desire, if not necessity, for providing a separate electric control for each individual outlet leading to the several heaters.

Accordingly in a desire to meet trade conditions, one of the primary objects of the present invention is to provide a simple form of bracket of the type outlined which

will accommodate a greater number of heaters than was possible with similar types of devices now known, while maintaining a compact construction of approximately the dimensions of similar chandeliers with which the trade is accustomed, and at the same time to maintain the separate and independent adjustability of each of the counterweighted heaters while providing a thermal control for the heaters both individually and en bloc.

Due to different ways in which the different hairdressers divide the hair on a person's head, different users require a different number of heaters, some using as few as sixteen heaters and therefore requiring but sixteen outlets for the electric current while others use as high as forty-eight heaters and therefore require a correspondingly large number of outlets. To meet this demand for a variable number of outlets from the chandelier, and at the same time to obtain a minimizing of manufacturing cost, the invention features the standardizing of certain parts so as to be interchangeable with similar parts having a different number of outlets. In this way there may be carried in stock certain basic parts which can be utilized for all usual sizes of chandeliers, and also to carry in stock several different sizes of attachments each having different number of outlets. In this way when an order is received for a chandelier with a definite number of outlets, the basic part can be assembled with that character of associated parts which, when assembled, will fill the required order and in this way different size chandeliers may be supplied quickly from a stock of relatively few standardized parts.

Apparatus of the character under discussion are subjected to long, continuous use and not infrequently rough usage. Accordingly, another object of the invention is to provide a construction in which those parts which are most liable to injury or wear can be readily replaced, practically without interruptions to the continuity of action of the remaining parts.

In order to attain this object, the invention features the use of standardized parts, such as certain well known form of plug and socket outlets with independent switches for controlling the current leading to the several heaters and also features the utilization of standard forms of main or gang switches

for controlling banks or sets of the heaters, which outlets and switches can be readily replaced in the assembled units forming the structural parts of the chandelier. In general the type of disclosure features the ready demountability of the electrical outlet elements and current control elements in a situation where a relatively large number of electric outlets must be confined within relatively small space limitation, and at the same time the present disclosure features a freedom of adjustment for each individual heater in their closely associated relation about a person's head without interference with the electro-thermal controls.

Still another object of the invention is to provide a simplified form of device of the type outlined which will permit ready accessibility to its interior without excessive dismantling of parts and at the same time to provide an article which will be ornamental in appearance and pleasing in appearance while minimizing the number of parts.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:—

35 Figure 1 is a view in side elevation of a preferred embodiment of the invention;

Figure 2 is an enlarged fragmentary view of the under-side of a portion of the construction shown in Figure 1 with one arm shown in full line and a ghost line showing suggesting the use of a longer arm.

40 Figure 3 is a vertical sectional view taken approximately on the line 3—3 of Figure 2;

45 Figure 4 is a transverse sectional view taken approximately on the line 4—4 of Figure 2;

Figure 5 is a transverse sectional view taken on the line 5—5 of Figure 2;

50 Figure 6 is a plan view of the guiding bracket shown in side elevation in Figure 1;

Figure 7 is a fragmentary view in plan of a portion of the head bracket shown in side elevation in Figure 1; and

55 Figure 8 is a transverse sectional view taken on the line 8—8 and showing one of the counterweight supporting pulleys.

In the following description and in the claims, parts will be identified by specific names for convenience of expression but they are intended to be as generic in their application to similar parts as the art will permit.

60 In the drawings and referring first to

Figure 1 for a general description of the device there is shown a depending support 10 formed of a length of square tubing, designed to be secured to the ceiling as is usual in bracket constructions. The lower end of the support is fitted into a hollow foot bracket 11 which is of general rectangular box-like form with an open bottom 12. A plurality of socket containing arms 13 extend radially from the sides of the bracket and provide supports for a plurality of longitudinally spaced apart plug and socket connections 14. The arms 13 are of square, tubular construction with their inner ends fitting about bosses 15 projecting from each of the four vertically extending sides 16 of the foot bracket. The arms are demountably secured in place by some readily removable fastening means and as an illustration of one such means the drawing discloses pins 17. The outer end of the arms are finished off in some neat manner and for this purpose plugs 18 are shown telescoped into the arms. It is a feature of this disclosure that the outlets for the electric current are positioned close together so as to obtain the greatest possible number of outlets with the least length of arm, it being understood that excessive lengths of arms are objectionable. The connection 14 includes a conventional form of cylindrical socket 19 provided with an electric switch controlled by oppositely extending finger pieces 20. A screw-plug 21 of usual form is demountably screwed into each socket and is connected electrically to a flexible conductor 22 leading to one of the electric heaters 23 usually employed in practicing the art of permanent hair waving. One side of the arm, in the illustrated example the lower side 24, is provided with a plurality of circular openings 25 in which the sockets 19 are inserted; or the opening 25 may be outlined by a sleeve 26 constituting a holder for receiving the barrel portion 27 of the socket. The plug engaging ends of the sockets, projecting exteriorly of the arm in position to be readily engaged by the plug 21, and in the drawings the plugs lead from the bottom of the arm but this is optional. The sides of the arms are slotted from their upper edges as shown at 28, in which slots are contained finger pieces 20. The top side 29 of the arm is removable in its entirety so as to provide ready access to each of the sockets and to the conductors leading thereto. A cover 29 for the open top side is held in place by fastening means 30. In the full line illustration in Figure 2, six such sockets are illustrated, but it is to be understood that it is one of the features of this disclosure to provide arms containing a different number of sockets which may be carried in stock, and as an illustration 130

tration of one such arm the dotted outline in Figure 2 suggests a ten-socket arm which can replace the six-socket arm simply by removing the fastening means 17 at the boss 5 and substituting the longer for the shorter arm.

In the device disclosed four arms are illustrated to form a cross-head structure at the lower end of the chandelier, but it 10 will be understood that a greater number of arms may be used similarly by changing the character of the foot bracket to accommodate the greater number of arms.

It is desirable in a device of this character to provide, in addition to the individual control of each of the outlets, a gang control for one or more of the arms and for this purpose there is disclosed in the drawings two main switches 31 and 32 housed 15 within the foot bracket and separated by an insulating partition 33. One of the switches is operatively connected to control the sockets in two of the arms, and similarly the other switch is connected to the sockets in 20 the other two arms. Main electric leads 35 are positioned in the depending supports and extend to the switches 31 and 32 and conductors 36 leads from the main switches through openings 37 in the bosses 15 to the 25 several socket connections. The main switches are of a well known form and each includes a press button 38 and a pilot light 39 which is lit when its corresponding switch is "on." The bottom of the bracket 11 is 30 closed and the main switches demountably held in place by a cover plate 40 secured to the foot bracket by means of readily removable fastening screws 41. The cover 40 is provided with a plurality of openings 42 35 through two of which extends the push buttons 38 and through two others of which openings the pilot lights 39 are visible.

From this construction it is appreciated that the removal of the cover 29 permits 45 access to the sockets in the arms so that any one of them may be withdrawn, a new socket replaced or access may be provided to the several electric conductors leading to the sockets. Similarly the removal of the 50 plate 40 at the bottom of the foot bracket permits the dropping out from the bracket of the main switches so that they may be repaired or replaced whenever necessary.

With the large number of heaters which 55 may be used with the device disclosed it is necessary that the counterweights necessary to support the heaters be disposed to the greatest advantage in economizing space and in preventing interference of any one of 60 the counterweights with the adjacent counterweights. For this purpose the present disclosure features an arrangement which tends to hang the heaters in a circle close to the head of the person under treatment and 65 which will dispose the counterweights in an

out-of-the-way position close to the central support and in such spaced position that each of the counterweights will be free to fall independently of all of the other counterweights. For this purpose there is disclosed 70 a head bracket 50 demountably and adjustably secured to the depending support adjacent its upper end as shown in Figure 1. The bracket is split into two parts as shown in Figure 7 so as to embrace the 75 support without demounting the same from its connection with the ceiling. This upper bracket is provided with a plurality of pulleys 51 which pulleys are mounted in two concentric circles and are disposed with their 80 axes fixed in position and free to rotate in planes radially disposed with reference to the support as a center. Each of these pulleys is spaced a distance from the support relatively short compared to the distance 85 from the support of the corresponding socket outlet. The several pulleys are offset from each other circumferentially in the two circles as shown in Figure 7 so as to separate the cables forming part of the counterbalancing devices. 90

A guiding bracket 53 is formed in two parts as shown more particularly in Figure 6 and is clamped in adjusted position on the depending support between the head and 95 foot brackets. This bracket is of a spider construction and includes radially extending arms 54 projecting from a circular part 55, both the arms and circular part being provided with vertically extending guiding 100 apertures or eyes 56. These apertures are so disposed, that their distances from the support is relatively small compared to the distances from the support of the corresponding outlets and pulleys. In other 105 words considering one heater set, its socket is at a great distance from the support, the pulley is closer in to the support and the counterweight is closest to the support. The counterbalancing devices include a plurality 110 of separate means each designed to counterbalance the weight of one of the heaters. Each device includes a flexible cable 57 looped about one of the pulleys and with its outer fall 58 fastened at its lower end to one of the heaters 23 as shown at 59, or fastened to the conductor 22 leading to the heater as shown at 60, see Figure 1. The inner fall 61 of the cable is passed through one of the guiding apertures 58 and has a 115 suitable counterweight 62 at its lower end. It is understood by this arrangement that the heaters are best supported at least approximately in a circle or circles close to the person's head under treatment, and that the several counterweights are disposed 120 within the outer falls of the several cables and in an out-of-the-way position close to the support, but in such position that the counterweights are free to fall independent 125 130 135

of each other even though an extremely large number of such counterweights are disposed within narrow space limitations.

In operation it will be understood that the device is used as is well known with present types of similar devices now in use. The hair is suitably wrapped into strands and inserted in the different heaters and the heaters assembled with a porcupine-like effect on the person's head. By suitably manipulating the main or gang switches certain parts of the head may be heated for variable periods of time and by a suitable manipulation of the individual socket switches for certain individual strands of the hair that may be treated differently from other strands and in this way an accurate, definite control is attained in the application of heat to the different strands or parts of hair.

By means of a device of the character described it is possible to provide a greater number of heaters than has been possible heretofore. This is further made possible by the appearance on the market recently of an extremely small size socket and plug type of outlet and the device disclosed is particularly designed to accommodate their small sized sockets. Further the foot bracket is designed to accommodate conventional forms of main switches. In this way it is possible for a user to replace either the sockets or main switches by purchasing one of these articles from any electrical supply house without the inconvenience of awaiting receipt of special parts from the chandelier manufacturer.

The chandelier can be repaired by the hair-dresser who is unskilled in mechanics or electrical connections simply by following the printed directions which go with the chandelier. Further it is possible for the dealer who supplies the retail trade to meet demands for variable numbered electric outlets simply by keeping in stock different sized arms and to assemble the supports and bracket parts with the particular character of arms which will meet the demands for any usual number of outlets.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. A chandelier for supporting a plurality of electric heaters in operative position relative to a person's head in the process of waving the hair on the head, including a depending support, a plurality of horizontally disposed hollow arms extending ra-

dially from the lower part of said support, each of said arms provided with a plurality of closely positioned holders, each designed to receive a standard form of readily replaceable sockets adapted to be connected electrically to one of the heaters, a head bracket carried by the support and provided with fixed pulleys mounted above the arms for rotary movement in planes radially disposed relative to the support, a flexible cable looped about one of the pulleys with the outer fall of the loop adapted to be connected to one of the heaters and the inner fall supporting a counterweight disposed adjacent the support whereby the counterweight is disposed in an out-of-the-way position clear of the heaters.

2. A chandelier for supporting a plurality of electric heaters in operative position relative to a person's head in the process of waving the hair on the head, including a depending support, a plurality of horizontally disposed hollow arms extending radially from the lower part of said support, each of said arms provided with a plurality of closely positioned holders, each designed to receive a standard form of readily replaceable sockets adapted to be connected electrically to one of the heaters, a head bracket carried by the support and provided with fixed pulleys mounted above the arms for rotary movement in planes radially disposed relative to the support, a flexible cable looped about one of the pulleys with the outer fall of the loop adapted to be connected to one of the heaters and the inner fall supporting a counterweight disposed adjacent the support whereby the counterweight is disposed in an out-of-the-way position clear of the heaters and means disposed close to the support for guiding the inner fall of the cable and thus insuring the location of the counterweight close to the support.

3. A chandelier for supporting a plurality of electric heaters in operative position relative to a person's head in the process of waving the hair on the head, including a depending support, a plurality of horizontally disposed hollow arms extending radially from the lower part of said support, said arms being readily replaceable by similar arms of different lengths thereby to adapt the chandelier to carry a variable number of heaters, each of said arms provided with a plurality of closely positioned sockets adapted to be connected to the heaters, the number of sockets being dependent upon the length of arm used, means for demountably securing any of said arms in position on the support and electric conductors in said hollow arms leading to the several sockets.

4. A chandelier for supporting a plurality of electric heaters in operative position relative to a person's head in the process of

waving the hair on the head, including a depending support, a plurality of horizontally disposed hollow arms extending radially from the lower part of said support, said 5 arms being readily replaceable by similar arms of different lengths thereby to adapt the chandelier to carry a variable number of heaters, each of said arms provided with a plurality of closely positioned sockets 10 adapted to be connected to the heaters, the number of sockets being dependent upon the length of arm used, means for demountably securing any of said arms in position on the support and electric conductors in 15 said hollow arms leading to the several sockets and a main switch carried by the support for simultaneously controlling all of the sockets in the arm.

5. A chandelier for supplying electric current to a plurality of heaters in the process 20 of hair waving, comprising a depending support, a foot bracket provided with means for supporting a socket containing arm, a hollow tube square in cross-section demountably secured at one end to said means and 25 adapted to contain electric conductors, one side of said arm provided with apertures forming holders adapted to contain electric sockets connected to the conductors and another side of said tube being removable to 30 provide access to the sockets and to the conductors leading thereto.

6. In a device of the class described, the combination with a depending support, a 35 foot bracket at the lower end thereof, a main switch in said bracket a box-like hollow arm extending from said bracket, one side of said arm provided with holders, electric sockets fitted in said holders and removable as units 40 therefrom, conductors in the support leading to the switch and conductors in the arm leading to the sockets, said arm having means providing access to the plugs and their conductors.

45 7. In a dome of the class described the combination of a depending support, a head bracket secured to said support adjacent its upper end and provided with a plurality of 50 pulleys spaced relatively great distances radially from the support and mounted for rotary movement in radially extending planes, a foot bracket at the lower end of the support, a plurality of arms extending horizontally from the foot bracket, electric sockets 55 fitted in said arms with each socket spaced at a relatively short distance from the support compared to the distance of its corresponding pulley from the support, electric hair waving heaters, flexible conductors including plugs, connecting the heaters with the sockets, flexible cables connected at one end to the flexible conductors to support the heaters, and passed about the pulleys and a 60 counterweight at the other end of the cables, 65 said counterweights being all grouped so as

to fall close to the support and in this way not interfere with the heaters.

8. In a dome of the class described, the combination of a depending support, a head bracket secured to said support adjacent its upper end and provided with a plurality of pulleys spaced relatively great distances radially from the support and mounted for rotary movement in radially extending planes, a foot bracket at the lower end of the support, a plurality of arms extending horizontally from the foot bracket, electric sockets fitted in said arms, with each socket spaced at a relatively short distance from the support compared to the distance of its corresponding pulley from the support, electric hair waving heaters, flexible conductors including plugs, connecting the heaters with sockets, flexible cables connected at one end to the flexible conductors to support the 80 heaters, and passed about the pulleys and a counterweight at the other end of the cables, said counterweights being all grouped so as to fall close to the support and in this way not interfere with the heaters and a guiding 85 bracket positioned on the support intermediate the foot and head brackets and provided with guiding apertures for containing the fall of the flexible cable provided with the counterweights.

9. In a chandelier of the type described, the combination of a depending support, a means adjacent the lower end of the support, provided with an electric outlet, a hair waving unit including a heater, an electric connection for engaging the outlet and a connecting flexible cable between the heater and connection, means for counterbalancing the weight of the heater including a pulley disposed with its axis fixed in position between the support and a vertical line passing centrally through the outlet, a cable passed over the pulley with its outer fall connected to the unit to support the heater, guiding means relatively close to the support for holding the inner fall of the cable close to the support and a counterweight on the end of the inner fall.

10. In a chandelier of the type described, the combination of a depending support, a plurality of arms adjacent the lower end of the support, each arm provided with a plurality of electric outlets positioned different distances radially from the support as a center, a head bracket provided with a plurality of pulleys disposed approximately in concentric circles about the support, a cable guiding bracket secured to the support and provided with apertures disposed approximately in concentric circles, and a plurality of cables with one fall of each cable passed about one of the pulleys adapted to have one fall thereof connected to a hair waving heater, and the other fall thereof passed through one of the apertures and terminat-

ing in a counterweight, said pulleys and apertures being disposed to maintain the cables in spaced apart position thereby to minimize interference with each other.

- 5 11. In a device of the class described, the combination of a box-like foot bracket opened at the bottom, a main switch demountably positioned in said bracket and provided with a control button and a pilot 10 light, a cover for closing the open bottom, said cover provided with apertures through which depend the control button and the pilot light so that access may be provided to the button and the light will be visible 15 when the current is on, hollow arms extending from the bracket and each provided with a plurality of openings, electric sockets each provided with its separate switch mounted in said opening and electric conductors within the arms and bracket connecting the sockets with the main switch. 20
12. In a device of the class described, the combination of a box-like foot bracket opened at the bottom, a main switch demountably 25 positioned in said bracket and provided with a control button, a cover for closing the open bottom, said cover provided with an aperture through which depends the control button so that access may be provided to the button, hollow arms extending from the bracket and each provided with a plurality 30 of openings, electric sockets each provided with its separate switch mounted in said opening and electric conductors within the arms and bracket connecting the sockets with the main switch. 35
13. In a chandelier of the type described, the combination of a depending support, a box-like foot bracket secured to the lower 40 end of said support, a plurality of hollow arms extending radially of the bracket, each of said arms provided with a plurality of closely positioned electric outlets, each adapted to have an electric hair waving 45 heater detachably connected thereto, each of said outlets provided with a switch accessible from the outside of its supporting arm and each switch independent of the switches controlling the other outlets and 50 a main controlling switch positioned in the foot bracket and operatively connected to control simultaneously all of the outlets in one of the arms. 55
14. In a chandelier of the class described, the combination of a hollow foot bracket provided with a boss projecting from one side thereof, a tubular arm telescoping said boss and opening therethrough into the bracket, means for demountably securing 60 the arm to the boss, a plurality of closely positioned sockets demountably fitted in said arm and with parts extending therefrom, certain of said parts adapted to provide means for connecting the sockets with an 65 electric hair waving unit and other means

constituting a control for the current passing through the sockets and electric conductors within the arm leading from the sockets into the bracket.

15. In a chandelier of the class described, the combination of a hollow foot bracket provided with a boss projecting from one side thereof, a tubular arm telescoping said boss and opening therethrough into the bracket, means for demountably securing the arm to the boss, a plurality of closely positioned sockets demountably fitted in said arm and with parts extending therefrom, certain of said parts adapted to provide means for connecting the sockets with an electric hair waving unit and other means constituting a control for the current passing through the sockets and electric conductors within the arm leading from the sockets into the bracket, said arm including a removable cover permitting access to the sockets and their electric conductors to replace or repair the same. 75

16. An article of manufacture constituting one of a series of replaceable arms on a chandelier, provided with means for securing the same in place on the chandelier, said arm provided along one side with a plurality of openings, each designed to receive a complete electric socket, the opposite side 95 of the arm being open to permit ready access to each of the sockets. 90

17. A chandelier for supporting a plurality of electric heaters in operative position relative to a person's head in the process of waving the hair on the head, including a depending support, a plurality of horizontally disposed hollow arms extending radially from the lower part of said support, said arms being readily replaceable by similar arms of different lengths thereby to adapt the chandelier to carry a variable number of heaters, each of said arms provided with a plurality of closely positioned sockets adapted to be connected to the heaters, the number of sockets being dependent upon the length of arm used, means for demountably securing any of said arms in position on the support and electric conductors in said hollow arms leading to the several sockets. 100 105 110 115

18. A chandelier for supplying electric current to a plurality of heaters in the process of hair waving, comprising a depending support, a foot bracket provided with means for supporting a socket containing arm, a hollow tube demountably secured at one end to said means and adapted to contain electric conductors, one side of said arm provided with apertures forming holders adapted to contain electric sockets connected to the conductors. 120 125

19. In a device of the class described, the combination of a box-like foot bracket opened at the bottom, a main switch de- 130

mountably positioned in said bracket and provided with a control button, a cover for closing the open bottom, said cover provided with apertures through which depend 5 the control button, hollow arms extending from the bracket and each provided with a plurality of openings, electric sockets mounted in said opening and electric conductors within the arms and bracket connecting the sockets with the main switch.

10 20. In a device of the class described, the combination of a foot bracket, a main switch

positioned in said bracket and provided with a control button, hollow arms extending from the bracket and each provided with a 15 plurality of openings, electric sockets each provided with its separate switch mounted in said opening and electric conductors within the arms and bracket connecting the sockets with the main switch. 20

Signed at New York city, in the county of New York and State of New York this 23rd day of June, A. D. 1921.

ERNEST UNGER.
